UNITED STATES PATENT OFFICE.

LEWIS E. McCONNELL, JR., OF MONTCLAIR, NEW JERSEY, ASSIGNOR TO THE W. F. POWERS COMPANY, OF NEW YORK, N. Y., A CORPORATION OF NEW YORK.

BILL FILE.

Application filed June 22, 1928. Serial No. 287,420.

This invention relates to that class of bill files that comprise a combination of an advertising card calendar with a bill hook that is adapted to lay flat with the card for mailing or packing, and is capable of being turned to a position at right angles to the card and be held firmly in such position so as to be used for filing bills or the like.

An embodiment of the invention is shown 10 in the accompanying drawings, in which

Figure 1 is a front view of a calendar card equipped with a bill hook.

Figure 2 is a vertical section through the center of the card showing the bill hook in 15 position to be used.

Figure 3 is a similar section showing the hook in process of being slid upward so as to permit of its being turned.

Figure 4 is a front view of the lower part 20 of the card showing the hook laid over on the card in position for mailing or packing.

As a support for the bill hook I may use a card 1 to the upper part of which is secured a calendar pad 2. The bill hook 3 comprises 25 a straight shank 4 with the lower part curved as shown at 5 to form a hook upon which bills or other memoranda may be impaled, and at the upper end a downwardly turned hook portion 6. The shank portion 4 is passed 30 through two vertically aligned holes 7, and when in use as a file the rear hook 6 is adapted to engage over the lower edge of the upper hole and thus form a support that will hold the filing hook 5 in a position at right angles

to the card. When it is desired to pack or 35 mail the card the shank 5 is slid upward with the hook sliding past the body of the card, as shown in Figure 3. To facilitate this the card is cut as at 8 with a circular cut forming a flap 9 that will bend outwardly enough to 40 let the shank slide by without ripping the card. The flexure of the flap allows the shank to slide either in front of the card or behind the card, as shown in Figure 3. When the hook has been so elevated it may be turned 45 so as to have the parts 5 and 6 lie flat against the card so as to present a two dimensional article that will be easily mailed or packed. When the hook is in the filing position, however, the flap 9 may be restored to the plane 50 of the card and the card will then present an even flush surface.

I claim:—

The combination comprising a display card and a file hook, the card having upper and 55 lower orifices through which the file hook passes, the upper hole being located in a flap formed in the card so as to permit the flexure of the card at the upper hole, the said hook having a bent down hook at the upper rear 60 end adapted to engage over the card at the base of the flap, the said flap permitting the said hook to slide up past the flap for its collapsed position, and to be restored to its flush position when the hook is in the filing position. 65
